UNITED STATES PATENT OFFICE.

WILLIAM W. WALLACE, OF CHICAGO, ILLINOIS, ASSIGNOR TO NEW YORK BRICK HANDLING CORPORATION, OF NEW YORK, N. Y., A CORPORATION OF NEW YORK.

LIFTING FORK.

Application filed February 4, 1926. Serial No. 85,908.

My present invention relates to lifting devices and more particularly to an improved loading and dumping fork for use in connection with the mechanical handling of brick. The principal object of my invention, therefore, is an improved brick lifting fork.

In the handling of brick by mechanical means, it is desirable and, in fact, necessary that the bricks be handled in units, such units being of any desired size. These units are usually built up after the preliminary drying operation on the brick and are then brought by a lifting fork into position where they are built into a kiln. The kiln is afterwards burnt and the completely burnt brick are removed from the kiln in units by a lifting device and carried to a truck, car, barge or any desired delivery device. With further improved methods of manufacturing brick, it has been found desirable to lift the unit on a fork and when the unit has been brought to the place of delivery, deposit same in position and then remove the fork from beneath such unit, thereby depositing and leaving the unit in stacked formation on the delivery device. For this reason, a lifting fork with pivoted tines or equivalent device is not necessary and therefore the lifting device may be made considerably more rigid than has heretofore been possible. The units of brick are built up upon so called "finger courses", between such finger courses the tines of the lifting fork are placed. In former constructions, it was usual to leave the finger courses in position and merely lift that portion of the brick unit lying thereon. This practically necessitated the dumping of the unit of brick off the fork when the same was brought to the point of delivery.

In my present invention I have obviated the objectionable features of prior apparatus of this type and the present invention is to be considered as an improvement over the fork shown in my Patent No. 1,564,652, dated December 8, 1925. In my present invention, I have shown improved means for gripping and holding the individual bricks comprising the finger courses and am thereby enabled to lift an entire unit of brick, including the finger courses, at a single operation. I have devised an entire gripping means whereby the finger courses are positively held on yielding tension, the tension depending upon the weight of the unit of brick so that the greater the weight of the brick, the greater the tension on the holding means.

Another object of my invention is an improved brick lifting fork, having in combination therewith, means for gripping finger courses of a unit of brick.

A further object of my invention is an improved brick lifting fork, having in combination therewith, an improved means for yieldingly holding and gripping the finger courses of a unit of brick.

Other objects and novel features of the construction and arrangement of parts comprising my device will appear as the description of the invention progresses.

In the accompanying drawings illustrating the preferred embodiment of my invention,

Fig. 1 is a side elevation,

Fig. 2 is a rear elevation,

Fig. 3 is a fragmentary plan elevation of a device showing the gripping fingers in operative position,

Fig. 4 is a fragmentary plan view similar to Fig. 3 but with the gripping fingers in inoperative position.

Fig. 5 is a sectional side elevation on the line 5—5 of Fig. 4,

Fig. 6 is a fragmentary sectional end elevation on the line 6—6 of Fig. 2,

Fig. 7 is a sectional plan view on the line 7—7 of Fig. 5,

Fig. 8 is a plan view on the line 8—8 of Fig. 5, and

Fig. 9 is a sectional elevation on the line 9—9 of Fig. 8.

Referring to the drawings, 10 designates a base provided on its lower face with a longitudinal extending rib projection 11 and secured to the lower face by bolts and nuts 12 and 13 respectively are a plurality of parallelly arranged lifting fingers 14, the upper surface of the rear end of each of these fingers being provided with a groove that operates with a longitudinal rib 11 on the base 10. The rib and groove prevent a rotary movement of the fingers 14 with respect to the base 10. The fingers 14 are spaced apart from each other a distance slightly greater than the width of two bricks 15, as shown in Figs. 3 and 4. By this construction, it is possible to slide the fingers 14 between the

- rows of brick 15, such brick constituting the finger courses of a unit of brick. Secured to the lower rear face of the base 10 at intervals along the length thereof are bearings 16, 5 the bearings being in alignment with each other and rotatably mounted in the bearings is a finger clamp shaft 17. Each of the bearing members 16 are provided on their lower face with a shaft 18 on which is mounted for 10 rotation an anti-friction wheel 19 to facilitate travel of the apparatus along the ground or other place where the same is to be worked. Also secured to the shaft 17 at intervals along its length are crank arms 20, 15 the number of crank arms 20 being equal in number to the fingers 14 attached to the base 10. Pivotaly attached to the lower free end of each of the crank arms 20 is one end of the member 21, this member on its free end 20 being internally threaded to receive the externally threaded end of a finger rod 22, such threaded end being provided with a lock nut 23 for holding the member 21 and finger rod 22 in adjusted position. The fingers 14 are hollow and the finger rods 22 are 25 slidably mounted therein, one finger rod 22 for each finger 14. Secured to each of the finger rods 22 by pins 24, are collars 25, these collars being arranged in pairs and between 30 each pair and on the rod 22 is a coiled spring 26, as clearly shown in Fig. 7. Adjacent to one of the collars 25 of each pair of collars is a spring crosshead 27, each crosshead being provided with radially extending pins 28. There are a plurality of pairs of collars 25 on each rod 22 and therefore a plurality 35 of spring crossheads 27 on each rod 22. A side wall of each of the fingers 14 adjacent to the spring crosshead 27 is provided with a cut out portion 29, and pivotally mounted in 40 each of the cut out portions 29 on pin 30 is a member 31, this member on its inner end being provided with slotted ears 32, these ears encircling the pins 28 on each side of the 45 spring crosshead 27. To the end of each of the members 31, designated as finger levers, are pivotally mounted finger clamps 33. When the rod 22 is moved to the left, as shown in Figs. 7 and 8, the pairs of collars 25 attached thereto, move also to the left, as 50 does the coiled spring 26. The tension of the coiled spring 26 keeps the spring crosshead 27 in engagement with its associated collar 25 and the pins 28 thereon engaging with the ears 32 of the finger lever 31 rotate such finger levers in an anti-clockwise direction around the pin 30, thereby bringing the finger clamps 33 outwardly laterally from the fingers 14 and into engagement with the finger courses 15. The continued movement of the rod 22 to the left will cause the clamping fingers 33 to force the finger courses 15 into engagement with the adjacent finger 14, as 55 clearly shown in Fig. 3, and as the movement of the rods 22 to the left continues, the 60
- spring crosshead 27 will become separated from its associated collar, as shown in Fig. 8 and it will be obvious that under these conditions the finger clamp 33 is yieldingly held against the finger courses 15 by the compression spring 26. 70
- Formed on the base 10, adjacent to each end of the upper surface thereof are members 34. To each of the members 34 and on each side thereof, secured by bolts 75 and nuts 35 and 36 respectively, are vertical bars 37. These bars are secured at their upper ends to the ends of a framework designated generally by the numeral 38. Secured to the upper central portion of the base 10 are vertical braces 39 which extend forwardly, as shown in Fig. 2 and are secured to the framework 38, also to the inner ones of the bars 37. At each end of the framework 38 and extending forwardly therefrom is a member 40. In each of these members 40 is secured parallelly arranged shafts 41 and 42 and on these shafts are rotatably mounted the levers 43 and 44 respectively. The inner ends of the levers 43 and 44 are connected together by means of a pivotally mounted connecting link 45 and also the inner ends are provided with abutting faces 46 and 47 respectively which prevent too great a rotary movement of the levers 43 and 44 in one direction. Each of the levers 43 are provided at their lower rear ends with an elongated slot 48, in which is slidably mounted a pin 49 and pivotally mounted on the pin 49 is a downwardly depending member 50. The lower free end of the member 50 is internally threaded to receive the upper threaded end of a connecting rod 51, a lock nut 52 being provided on the connecting rod 51 for maintaining such connecting rod and member 50 in adjusted position. The lower end of each of the connecting rods 51 is threaded and screws into the upper end of members 53, a lock nut 54^a being associated therewith for 100 adjusting purposes. Each of the members 53 is pivotally attached to the outer end of crank arms 54^b secured to the shaft 17. 105
- The rear ends of the levers 43 and the forward ends of the levers 44 are provided with pivotally mounted shackles 54 with which are associated shackles 55 pivotally mounted on a lifting platform 56, the shackles 54 and 55, together with levers 43 and 44, constituting a four point suspension means for the 110 apparatus. 115
- Formed integral with each of the levers 43 and extending upwardly therefrom on each side thereof, are members 58, these members being spaced apart from each other, 120 as clearly shown in Fig. 8 and provided on their front edges with grooves 59. Fitting into such grooves 59 are pins 60 formed on opposite sides of a cup-shaped holding member 61. Formed on each side thereof and 125
- 130

extending forwardly therefrom are ears 62 similar to the ears 58 above described, and on the rear edge of each of these ears is formed a groove 63 which engages with pins 64, formed on opposite sides of a cup-shaped spring holding member 65. The open end of each of the spring holding members 61 and 65 is located a compression spring 66, this compression spring, as will be seen from 5 an inspection of Fig. 6, tending to rotate the levers 43 and 44 about their pivot points so as to move the outer free ends thereof downwardly and thus to cause a movement of the rods 22 to the right, as shown in Figs. 10 7 and 8. In order to vary the tension of the springs 66, I have provided the members 61 and 65 with adjusting screws 67, the inner end of these screws engaging with the springs 66. The weight of the load on the 15 fingers 14 is balanced by the tension springs 66.

The device, as above described, is applicable to the picking up and carrying of a unit of brick by means for yieldingly engaging the finger courses of such unit. It may happen that it will be desired to merely lift a unit of brick without regard to the finger courses thereof and I have, therefore, provided means for locking the finger 25 clamps 33 in enclosed or in the inoperative position.

Referring to the drawings, there is shown secured to the top surface of the frame 38, bearing standards 70 and in these bearing 30 members is rotatably mounted a shaft 71. Secured to the rear end of the shaft 71 is a crank handle 72 and by means of which the shaft 71 may be rotated. Secured to the shaft 71, intermediate its ends, is a flange 35 73 and extending laterally outward from said flange, diametrically with respect to each other, are crank pins 74. Pivots connected to each of the crank pins 74 are connecting rods 75, one of each of these 40 connecting rods being arranged on each side of the shaft 71, as clearly shown in Fig. 2. The other ends of each of the connecting rods 75 are pivotally attached to bars 76 slidably mounted in bearing members 77 secured to the top surface of the frame 38. Each of the sliding bars 76 is provided at the end, remote from the connecting rods 75, with U-shaped end members 78 of a size 45 adapted to fit between the cup-shaped spring holding members 61 and 65. It is obvious, therefore, that if the U-shaped members 78 are placed between the members 61 and 65, it will be impossible for such members 61 and 65 to have any movement 50 toward each other, and therefore, the members 61 and 65, being held immovable, the pins 60 and 63 will likewise be held immovable and the ears 58 and 62, contacting with such pins 60 and 63, will prevent a rotary 55 movement of the levers 43 and 44 in such

direction as to have the outer free ends thereof move upwardly. If there can be no upward movement of the outer free ends of the levers 43 and 44 there will of course be no upward movement of the connecting 70 rods 52 and therefore no movement to the left of the rods 22, as viewed in Figs. 7 and 8. Movement to the left of the rods 22 being prevented, the finger clamps 33 will remain in the position shown in Fig. 7 75 that is housed within the limits 14. Therefore, when the locking device just described is utilized, the apparatus may be utilized as a lifting fork to pick up and load on top of the fingers 14, as is the case of the 80 lifting forks heretofore manufactured.

It will be noted from an inspection of the drawings, and particularly Fig. 9, that the upper portion of the fingers 14 is of considerable less width than the lower portion 85 of such fingers. There is considerable advantage to be obtained in making these fingers in this manner. As is well known, when said machine grips the grip courses, it only grips the bottom part of the bricks 90 and, therefore, pinches these bricks in so that there is less room in between the rows of the fingers at the top than there is in between the bottom rows of the grip fingers, and, therefore, when taking these brick out 95 with the new fork, forming the subject matter of the present invention, there will naturally be less room for the fingers to get in between the top of the brick courses than there is at the bottom of the brick courses. 100

While I have necessarily shown the preferred embodiment of my invention somewhat in detail, it is to be understood that I may vary the size, shape and arrangement of parts comprising the device within wide 105 limits without departing from the spirit of the invention.

Having thus described my invention, what I claim as new is:

1. An improved lifting fork comprising a 110 plurality of parallelly arranged fingers, pivotally mounted means for engaging material located between said fingers, a rod slidably mounted in each finger and springs on each rod cooperating with the material, and engaging means for yieldingly holding said material holding means in inoperative position.

2. An improved lifting fork comprising a plurality of parallelly arranged fingers, 115 means associated therewith for engaging material located between the fingers, rods slidably mounted in each finger, springs located on said rods, connecting means between said springs and the material engaging means and means for moving said rods to move the springs into position to yieldingly hold the material engaging means in inoperative position. 120

3. An improved lifting fork comprising a 130

base, a plurality of parallelly arranged lifting fingers secured thereto and extending laterally outward therefrom, material engaging means pivotally mounted in said fingers, means for moving said fingers into engaging position with material placed between the fingers and yieldingly holding the same in inoperative position and suspension means for said base for moving said rods 10 and yieldingly holding rods in inoperative position.

4. An improved lifting fork comprising a base, a plurality of parallelly arranged lifting fingers secured thereto and extending laterally outward therefrom, said fingers being of greater cross-sectional area at their bottom portion than at the top portion, material engaging means pivotally mounted in said fingers, means for moving said fingers into engaging position with material placed between the fingers and yieldingly holding the same in inoperative position and suspen-

sion means for said base for moving said material engaging means into inoperative position.

5. An improved lifting fork comprising a plurality of parallelly arranged fingers, each provided with a longitudinally arranged passage extending throughout the length thereof, means associated therewith for engaging material located between the fingers and normally housed within the limits of such fingers, a rod mounted in each passage and slideable with relation to the fingers, springs located on said rods, connecting means between said springs and the material engaging means, and means for moving said rods to move the springs into position to yieldingly hold the material engaging means in inoperative position.

In testimony whereof, I have signed my name to this specification.

WILLIAM W. WALLACE.
